WHEEL CONSTRUCTION

Filed Jan. 2, 1926

Basil. Meigs,

INVENTOR.

Attorney

UNITED STATES PATENT OFFICE

BASIL MEIGS, OF WASHINGTON, DISTRICT OF COLUMBIA

WHEEL CONSTRUCTION

Application filed January 2, 1926. Serial No. 78,937.

This invention relates to an improvement in wheels for vehicles such as automobiles and the like, and represents a carrying forward of the invention set forth in the Torkel-
son and Meigs Patent No. 1,461,690, dated July 10, 1923.

In its general aspect the present invention embodies a main load sustaining member and a cover member for concealing and masking the protruding or projecting axle cap customarily found on wheels of both the disk and spoke type. More specifically, however, the invention about to be described is directed to the improved cover disk having special features of construction and design which not only materially reinforce and strengthen the same but at the same time facilitate its use and application to wheels of the wooden spoke type, thereby not only giving added strength to this type of wheel but also adding to the ornamental appearance thereof and providing therefor an anti-collision feature which is very desirable.

It is well known that wheels of the wooden spoke type break easier than wheels of the wire spoke or steel disk type, and therefore the present invention when used in connection with a wheel of the wooden spoke type gives added strength and rigidity thereto while at the same time providing an increased factor of safety. In that connection, however, it is to be understood that the application of the improved cover plate is not limited in its usefulness to wheels of the wooden spoke type but may also be used in wheels wherein a metal disk constitutes the main load sustaining or load carrying member.

A further object of the invention is to provide a novel cover plate formed to provide means for stiffening the plate or disk at its point of attachment with the felloe of the wheel so that the same will firmly engage the felloe in such a way as to prevent rattling or squeaking and at the same time distributing the vertical loading strains and horizontal side thrusts more adequately throughout the circumference of the felloe.

A still further object of the invention is to provide a cover member which may be

used in connection with standard wheels now on the market so that no mechanical change or alteration is required to effect the installation of the present invention.

With the above and other objects in view which will more readily appear as the nature of the invention is better understood, the same consists in the novel construction, combination and arrangement of parts herein-after more fully described, illustrated and claimed.

A preferred and practical embodiment of the invention is shown in the accompanying drawings, in which:

Figure 1 is a vertical sectional view of the improved wheel, the line of section being on the line 1—1 of Figure 2.

Figure 2 is a side elevation thereof.

Fig. 3 is a detail cross-sectional view taken on the line 3—3 of Fig. 2.

In carrying the present invention into effect it is proposed to provide a novel cover member designated generally as C adapted to be applied to the felloe B of a wheel W having an axle A, the said cover member serving to completely seal and mask the axle as well as the spokes of the wheel W, or in case the wheel is of the steel disk type as shown in the patent referred to, it will cover the main load carrying disk.

The present novel type of cover is primarily designed to provide a felloe seat whereby the cover member may wedge tightly against the felloe; to provide a stiffened and reinforced construction having a stiffening and reinforcing shock bead placed where the deviation from the line of force has its greatest magnitude; to provide a cover member having curved surfaces which eject dirt and facilitate the maintenance of the wheel in a clean condition; to provide a disk which is designed to avoid striking against curb stones or similar projections above the normal level of the road bed; and also to provide a guard or shield for the axle which will not only avoid the ensnaring and striking of pedestrians but at the same time ward off the dangerous effect of collisions which often result from the axles or hub caps of passing cars striking together.

Referring to the drawings it will be observed that the outer peripheral portion of the member C is provided with an anti-rattle and stiffening flange designated generally as 1, the same having an outwardly projecting bead 2 provided with suitable openings for receiving the rim bolts so that when the rim lugs are applied the force thereof will firmly press the bead 1 to the side of the felloe. In that connection it will be observed that the stiffening flange or bead 1 includes an annular centering rib 3 which is formed in the opposite direction from the bead 2 thereby to engage with the inner circumference of the felloe. The said rib 3 provides in effect an inwardly projecting shoulder for engaging with the felloe or equivalent part, not only to provide a seat for the cover member but to also insure the transmission and distribution of strains and shocks to all parts of the wheel.

It will be observed that the stiffening flange 1 as well as the parts 4 and 5 of the wheel are substantially parallel to the plane of rotation of the wheel, and the part 4 is connected to the flange 1 by means of the offset curve 4a which is carried outwardly as far as may be on such a radius still to provide adequate curb clearance. Also the part 4 is connected with the part 5 by means of the compound curve surfaces 5a and 5b which are joined by a stiffening and reinforcing bead 6 which is placed where the deviation from the line of force has the greatest magnitude, and also stiffens the disk so that it may more adequately transmit shock directly to the main load sustaining member B—W.

The flange 1 which includes the compressible bead 2 and the centering rib 3 permits the cover member to be applied to felloes that are worn as well as those that are new, and the resiliency of the bead contributes greatly to the holding power of the rim lugs or clips. Also the rib 3, bearing as it does against the inside of the felloe, substantially at a corner thereof, enables the transmission of shock to all parts of the felloe, while without such a member as C, only the part of the wheel between the axle and the ground takes the load and the shock. In other words, since the present cover member circumvents, or is free of the hub cap or axle, the load is distributed above and below the axle, thereby adding greatly to the stability of the wheel.

The flat or substantially flat portion 5 at the center of the cover member not only provides the collision safety factor previously referred to but also tends to decentralize the wheel, as distinguished from wheels now in general use for the reason that it more adequately distributes the load as above referred to and at the same time produces an entirely different visual effect which permits of ornamentation, when desired, that will add great-

ly to the attractiveness and appearance of the wheel.

As shown in the drawings the cover member C is provided with means for permitting access to the valve stem at the outside of the wheel.

While of course any suitable and convenient means may be utilized in connection with the present cover to provide easy access to the valve cap for filling the tire with air, one way of accomplishing the desired result is by attaching a hood member 7 to the rear face of the cover adjacent the periphery thereof, the said hood 7 constituting a guide for a valve stem having a flexible portion. That is to say the hood 7 cooperates with an opening 7a in the cover disk to permit of the passage of the end 8 of a valve stem member designated generally as V, the said part 8 being provided with an annular shoulder 9 for engaging with the edge of the opening 7a when the valve is projected therethrough. The exposed end of the valve may be provided with a cap 10 as usual. Referring more particularly to the valve stem V it will be observed that the same consists essentially of the inflexible section 8 previously referred to and a main inflexible section 11, the said sections 8 and 11 being connected by a spring-like intermediate section 12 made of flexible steel or rubber. The section 8 is provided with the usual valve mechanism and is conveniently accessible from the outside of the cover disk, when the same is installed, to permit of the filling of the tire with air. In this type of construction it is not necessary to use a retaining nut on the valve stem, although it may be used if desired. However, often the retaining nut is not used on the ordinary valve stem and even in devices where it is accidentally or intentionally omitted it is seldom that much dirt is found to work into the felloe through the space between the valve stem and the valve stem opening in the felloe.

With the construction of the valve stem V shown in Figs. 1 and 3, in particular, it will be observed that when the stem is first thrust through the hole in the felloe and strikes the curved guide 7 it will pass through the opening 7a until the shoulder 9 engages over one edge of the opening thus preventing the stem jumping back into the tire body as it often does in structures now in use while other manipulation of the tire is going on. While the shoulder 9 is primarily designed to take the place of the retaining nut, nevertheless such nut may be used if desired.

From the foregoing it will be apparent that the present invention provides a cover member wherein the same is provided with adequate reinforcement where necessary to more effectively meet the particular conditions under which the disk is intended to be

used, while at the same time providing the other advantages herein set forth.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A wheel construction including in combination with the wheel having a felloe and mounted on an axle, a cover member having an attaching flange portion at its peripheral edge including an outwardly offset compressible stiffening bead adapted to be engaged by a rim lug to hold the same to the felloe.
  2. The combination of a vehicle wheel having a hub, of a cover plate having its peripheral portion adapted to be secured adjacent to the rim of said wheel, a guide member carried by the cover plate, and an inflating valve stem having a flexible portion whereby the valve stem may be deflected by said guide to be exposed at the outer face of the cover plate.
  3. A wheel construction including a member having a hub and a felloe, rim lugs carried by the felloe, and a disk member having a compressible peripheral bead adapted to register with the felloe and adapted to be engaged by the rim lugs.
- 35 In testimony whereof I hereunto affix my signature.
